UNITED STATES PATENT OFFICE.

ALVAN B. BROWN, OF GRAND RAPIDS, MICHIGAN, ASSIGNOR OF ONE-HALF TO CHARLES H. FIELD, OF GRAND RAPIDS, MICHIGAN.

SPRAYER.

1,232,489.

Specification of Letters Patent. Patented July 10, 1917.

Application filed August 28, 1916. Serial No. 117,217.

To all whom it may concern:

Be it known that I, ALVAN B. BROWN, a citizen of the United States, residing at Grand Rapids, county of Kent, State of Michigan, have invented certain new and useful Improvements in Sprayers, of which the following is a specification.

This invention relates to improvements in sprayers.

10 The objects of this invention are to provide an improved sprayer the structure of which is simple and durable, which is adapted to produce sprays of different character and which is very easily manipulated to produce such results and which constitutes a valve.

A further object is to provide an improved sprayer which is not likely to clog and should it become clogged is readily freed 20 from the obstruction.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing, forming a part of this specification, in which:

Figure I is a side view of a sprayer device embodying the features of my invention.

35 Fig. II is a central section through the nozzle of my improved sprayer, parts being shown in full lines.

Fig. III is a plan view of the plunger.

Fig. IV is a side view of the plunger.

40 Fig. V is a slightly modified structure embodying the features of my invention.

Fig. VI is a plan view of the plunger of the modified structure shown in Fig. V.

Fig. VII is a section on a line corresponding to line 7—7 of Fig. VI.

Fig. VIII is a central section of another modification of my invention.

In the drawing similar reference characters refer to similar parts throughout the 50 several views, and the sectional views are taken looking in the direction of the little arrows at the ends of the section lines.

Referring to the drawing, the nozzle body 1 is provided with a nozzle chamber 2 terminating in a plunger cylinder portion 3 at

its outer end. At its inner end the nozzle chamber has an internally threaded inlet connection 4 for the delivery pipe 5. The delivery pipe 5 is provided with a handle or grip portion 6, the hose 7 being connected to the butt of this grip portion.

The body 1 of the nozzle is externally threaded at its outer end to receive the tip member 8. The tip in the structure illustrated is formed of the member 8 and a disk-like member 9 having the discharge orifice 10 therein, the member 9 being retained within the member 8 by the annular flange 11 thereof.

An annular gasket 12 is disposed between 70 the disk 9 and the end of the body 1, the disk member 9 being clamped thereon by the tip member 8. The plunger 13 is arranged to reciprocate in the cylinder portion 3 and is provided with a stem 14 projecting through the opening 15 in the inner end of the body member at the side of the pipe 5.

A packing gland 16 is provided for the plunger stem. The plunger is adapted to 80 set against the gasket 12 and constitutes a valve for the nozzle. The plunger is provided with diagonally disposed peripheral groove-like passages or ports 17 which are closed when the plunger is seated. The inner end of the plunger is beveled at 18 so that when the plunger is retracted this beveled portion passing from the inner end of the cylinder portion provides supplemental portage, such supplemental portage is not, 90 however, brought into action until the plunger has been moved a considerable distance.

The pressure of the spraying fluid tends to seat the plunger and will normally accomplish that result. I, however, prefer to 95 employ a spring 19 which is arranged on the stem of the plunger to normally hold the plunger in its initial or closed position. This spring is of considerable advantage in that it provides a resistance for the operator to 100 pull against in manipulating the plunger actuating lever 20. The lever 20 is pivoted at 21 on the clip 22 carried by the pipe 5, the lever being connected by the link 23 to the plunger stem.

The plunger is provided with a needle-like projection 24 which projects into the delivery orifice 10 when the plunger is seated so that it is effectively freed from any obstruction which may collect therein.

105

110

In the modification shown in Fig. V the spring 19 is omitted. The ports 17 in this modification are formed in the body of the plunger, as distinguished from its periphery.

5 In the modification shown in Fig. VIII the plunger is of even diameter from end to end and the plunger cylinder has a chamfered portion 25 at its inner end which secures the supplemental regulated portage.

10 By thus arranging the parts I provide a very effective sprayer and one which delivers different characters of spray and a considerable range of sprays from wide to long, the variation being secured merely through manipulation of the plunger. When the plunger is but slightly opened broad short spray is secured. As the plunger is opened farther the spray is lengthened and narrowed. When the plunger is opened

15 to bring the beveled portion thereof into action to secure the additional or supplemental portage a forceful spray is delivered. When the plunger is fully opened a long narrow forceful spray is delivered, so that by simple manipulations I am able to produce a large range of sprays, that is, sprays of different character in order to meet the various requirements in practice and this simply by manipulation of the plunger lever. When the plunger lever is released the pressure will close it. When closed the plunger constitutes a valve, cutting off the spray and preventing any loss of the spray solution. A further advantage of cutting

20 off at the nozzle is that it prevents the dripping of the spray solution on the handle and also the loss of the spray solution which would be contained within the rod and the tip, it being common practice to arrange the valve at the handle. A further advantage of the construction is that by being able to fully control the spray it may be regulated to meet the requirements for spraying a small tree or shrub, a large tree or the trunk 25 or limbs of a tree, thus enabling the placing of the spray solution in a very effective manner and as desired.

I have illustrated embodiments which I have found to be very satisfactory. I have not attempted to illustrate or describe other 30 embodiments of my invention as I believe the disclosure made will enable those skilled in the art to which my invention relates to embody or adapt the same as circumstances 35 may render desirable.

Having thus described my invention, what I claim as new and desire to secure by Letters Patent, is:

1. In a sprayer, the combination of a nozzle body having a nozzle chamber terminating in a plunger cylinder portion at its outer end and provided with an inlet at its inner end, a delivery pipe connected to said inlet, a nozzle tip threaded on said body member 45 and having a discharge orifice, an annular

gasket disposed between said tip and the end of said body, a plunger arranged to reciprocate in said cylinder portion and seat against said gasket constituting a valve and having diagonally disposed ports, a plunger 70 stem arranged through the inner end of the nozzle body at the side of said delivery pipe, and a spring arranged on said plunger stem to normally hold said plunger on its seat.

2. In a sprayer, the combination of a nozzle body having a nozzle chamber terminating in a plunger cylinder portion at its outer end, a nozzle tip threaded on said body member and having a discharge orifice, an annular gasket disposed between said tip 75 and the end of said body, a plunger arranged to reciprocate in said cylinder portion and seat against said gasket constituting a valve and having diagonally disposed ports.

3. In a sprayer, the combination of a nozzle body having a nozzle chamber terminating in a plunger cylinder portion at its outer end, a nozzle tip threaded on said body member and having a discharge orifice, an annular gasket disposed between said tip 80 and the end of said body, and a plunger arranged to reciprocate in said cylinder portion and seat against said gasket constituting a valve and having diagonally disposed 85 peripheral ports, said plunger being beveled at its outer end to provide supplemental portage.

4. In a sprayer, the combination of a nozzle body having a nozzle chamber with a plunger cylinder portion, a nozzle tip having 100 a discharge orifice, an annular gasket disposed between said tip and said body, and a plunger arranged to reciprocate in said cylinder portion and seat against said gasket to constitute a valve and having diagonally 105 disposed ports, said cylinder and plunger being adapted to provide additional portage when the plunger is fully opened.

5. In a sprayer, the combination of a nozzle body having a nozzle chamber with a 110 plunger cylinder portion, a nozzle tip having a discharge orifice, an annular gasket disposed between said tip and said body, and a plunger arranged to reciprocate in said cylinder portion and seat against said gasket to constitute a valve and having inclined 115 ports, said plunger being provided with a needle projecting through said delivery orifice when seated, and a spring arranged to normally hold said plunger to its seat against 120 said gasket.

6. In a sprayer, the combination of a nozzle body having a nozzle chamber with a plunger cylinder portion, a nozzle tip having a discharge orifice, an annular gasket 125 disposed between said tip and said body, a plunger arranged to reciprocate in said cylinder portion and seat against said gasket to constitute a valve and having inclined ports, said plunger being provided 130

with a needle projecting through said delivery orifice when seated.

7. In a sprayer, the combination of a nozzle body having a nozzle chamber with a plunger cylinder portion, a nozzle tip having a discharge orifice, an annular gasket disposed between said tip and said body, a plunger arranged to reciprocate in said cylinder portion and seat against said gasket to constitute a valve and having inclined ports, and a spring arranged to normally hold said plunger to its seat against said gasket.

8. In a sprayer, the combination of a nozzle body having a nozzle chamber with a plunger cylinder portion, a nozzle tip having a discharge orifice, and a plunger in the form of a disk arranged to reciprocate in said cylinder portion and constituting a valve and having inclined ports extending from one end thereof to the other, said cylinder and plunger being adapted to provide additional portage when the plunger is fully retracted, said plunger being provided with a needle projecting through said delivery orifice when seated.

9. In a sprayer, the combination of a nozzle body having a nozzle chamber with a plunger cylinder portion, a nozzle tip having a discharge orifice, a plunger arranged to reciprocate into and out of said cylinder portion and provided with a member constituting a valve having inclined ports extending from one end thereof to the other, said cylinder and member being adapted to

provide additional portage when the plunger is fully retracted.

10. In a sprayer, the combination of a nozzle body having a nozzle chamber with a plunger cylinder portion, a nozzle tip having a discharge orifice, a plunger arranged to reciprocate into and out of said cylinder portion and provided with a member constituting a valve having inclined ports extending from one end thereof to the other, 40 said member being provided with a needle projecting through said delivery orifice when seated, and means for reciprocating said plunger.

11. In a sprayer, the combination of a nozzle body having a nozzle chamber with a cylindrical portion, a nozzle tip having a discharge orifice and provided with a valve seat secured to said cylindrical portion, a valve member slidable in said cylindrical portion having inclined ports extending from one end thereof to the other, said ports being closed when said valve member is seated on said valve seat, and means whereby said valve member may be reciprocated into and out of said cylindrical portion. 50

In witness whereof, I have hereunto set my hand and seal in the presence of two witnesses.
